UNITED STATES PATENT OFFICE

HERBERT AUSTIN, OF BROMSGROVE, ENGLAND

MOTOR CAR BODY FITTED WITH COLLAPSIBLE OR FOLDING TOP

Application filed November 18, 1929, Serial No. 407,981, and in Great Britain December 11, 1928.

This invention relates to motor car bodies of the type in which the upper portion of the rear of the body is adapted to be hinged back in relation to the lower portion, such 5 for instance as when it is desired to collapse the top; and the object of the invention is to provide means to lock the hinged part securely in its turned back position.

According to this invention means are provided whereby, when the folding portion has 10 been turned back, it is locked in such position at each side by a detent entering a notch in a plate or other part which is rigid with the folding part, such detent also preferably 15 entering a notch in an adjacent fixed plate so that on the engagement of the detent such plate or other part of the folding back becomes locked in relation to the fixed plate whereby the folding back is held rigidly in 20 its open position.

The invention is particularly adapted to a folding back portion used in conjunction with what is known as a "sunshine" hood; that is to say a folding top in which the 25 ends of hoop sticks supporting a flexible roof are adapted to slide along horizontal cant rails at the sides of the top of the body and down vertical rails at the rear corners thereof. In this case the detents may be carried 30 at the ends of the rearmost hoop stick each detent serving to lock the folding portion at the corresponding side.

In order that the invention may be clearly understood a convenient application thereof 35 to a motor car body fitted with a "sunshine" hood is described with reference to the drawing herewith, of which:—

Figure 1 is a fragmentary small-scale sectional view of the rear portion of a motor 40 vehicle showing the part of the back which is arranged to fold down.

Figure 2 is a view corresponding to Figure 1 showing the back in its folded down position and some of the hoop sticks resting thereon.

Figure 3 is a detached view to half scale showing the hinged parts in the position they assume when the back is in its raised or normal position.

Figure 4 is a view corresponding to Figure

3, but showing the parts in the position they assume when the back is turned down and locked; and,

Figure 5 is a view of the parts shown in Figure 3 as seen looking in the direction of 55 the arrow of that figure.

In the drawing:—A is the fixed part of the back of the body and B the upper or hinged part having screwed to it, at either side, a curved arm C pivoted to a bracket D secured against the inner face of an upright of the fixed back. Rigid with the arm C is a vertical plate E provided with a notch F. G is an upwardly extending portion of the bracket D provided with a notch H. J J denote hoop sticks (see Figure 4) each of which, at each end, carries a fitting K having pin M adapted to engage within channels N secured against the inner face of fixed rails P extending upwards from each side of the fixed portion of the back. To the fitting K, at each side of the rearmost hoop stick J, is secured a detent Q. The hoop sticks J J, when the roof is set up, have other hoop sticks J J interposed between them but the latter have no pin M and are therefore free of the channels. These hoop sticks are shown only in Figure 2.

To the plate E there is pivoted a downwardly extending rod R passing through a bottom flange S of the bracket D and the rod is provided with a pair of nuts T locked on its lower end. The bolt R thus serves to limit the downward movement of the moving part B.

When the part B is in its downmost position the notch F on the plate E comes opposite to the notch H of the fixed plate G; and, when the hoop sticks J are traversed down, each detent Q enters both the respective notches F 90 and H, thus locking the plate E in relation to the plate G. It will be noticed that the detent Q is somewhat wedge shaped and that the notches are shaped to correspond so that any tendency of the part B to rock causes the detent to wedge tightly in the notches. The wedge shape also facilitates the removal of the detent. As soon as the top is traversed forward and the rearmost hoop stick J raised, the detent, at each side, leaves the notches so 95 100

that the back of the vehicle is free to fold up on the closing of the top. This is usually effected by the pull of the fabric of the roof.

Having fully described my invention what 5 I claim and desire to secure by Letters Patent is:—

1. A motor vehicle body, a lower part of the back thereof, an upper part of the back which when closed is in the same plane as the 10 lower part and is hinged in relation to the said lower part and adapted to be turned back at right angles to open it, a hinge member in respect of said upper part a notch in said hinge member, and a detent adapted to be 15 brought into engagement with said notch to lock said upper part in its open position.

2. A motor vehicle body, a lower part of the back thereof, an upper part of the back which when closed is in the same plane as said 20 lower part and is hinged in relation to the said lower part and adapted to be turned back at right angles to open it, a hinge member in respect of said upper portion, a wedge shaped notch in said hinge member and a 25 wedge shaped detent adapted to be brought into engagement with said notch to lock said upper part in its open position.

3. A motor vehicle body, a lower part of the back thereof, an upper part of the back 30 thereof hinged in relation to said lower part and adapted to be turned back to open it, a hinge member in respect of said upper part a notch in said hinge member, a fixed plate adjacent said hinge member, a notch in said 35 fixed plate and a detent adapted to be brought into engagement with both said notches to lock said upper part in relation to said fixed plate when said upper part is in its open position.

4. A motor vehicle body, a lower part of the back thereof, an upper part of said back hinged in relation to said lower part and adapted to be turned back to open it, a hinge 45 member in respect of said upper part, a notch in said hinge member, rearwardly slid able transverse roof members, a detent operated by the rearmost roof member and adapted to be brought into engagement with said notch and said detent being withdrawn by the 50 agency of said roof member when it is moved towards its closed position.

5. A motor vehicle body, a lower part of the back thereof, an upper part of said back hinged in relation to said lower part and adapted to be turned back to open it, a hinge 55 member in respect of said upper part, a notch in said hinge member, rearwardly and downwardly slid able transverse roof members, a detent operated by the rearmost roof member and adapted to be brought into engagement with said notch when said roof member is moved to its open position and withdrawn therefrom as said roof member is moved towards its closed position.

6. A motor vehicle body, a lower part of

the back thereof, an upper part of said back hinged in relation to said lower part, and adapted to be turned back to open it, a hinge member in respect of said upper portion, a notch in said hinge member, rearwardly and downwardly slid able transverse roof members, a detent carried by the rearmost roof member and adapted to be brought into engagement with said notch when said roof member is moved to its open position and withdrawn therefrom as said roof member is moved towards its closed position.

7. A motor vehicle body, a lower part of the back thereof, an upper part of the back hinged in relation to the said lower part and adapted to be turned back to open it, a hinge member in respect of said upper part, a notch in said hinge member, a detent adapted to be brought into engagement with said notch to lock said upper part in its open position, a downwardly depending rod pivoted to said hinge member, a fixed plate through which said rod passes and stops on said rod to limit the movement of said hinge part in either direction.

In witness whereof I have hereunto signed my name this fourth day of November 1929.

HERBERT AUSTIN.
